By *Toulin and Toulin*,

Attorneys

Patented July 12, 1927.

UNITED STATES PATENT OFFICE.

CHARLES SAMUEL CLARKE, OF WICK, NEAR BRISTOL, ENGLAND.

CASEMENT WINDOW.

Application filed November 15, 1926, Serial No. 148,506, and in Great Britain August 14, 1926.

This invention relates to casement windows.

The object of this invention is to provide a casement window which will muffle or subdue external noises and yet permit the admission of air.

One form of window made in accordance with my invention is shown in the accompanying drawings of which:—

10 Fig. 1 is an elevation and

Fig. 2 is a sectional plan through line A—A.

The casement shown is made up of a rectangular frame formed by a right and left style *a* and *b* respectively, of a substantially deep character from back to front and a top and bottom *c* and *d*. Hinged to the front of this frame at the sides *a* and *b* are two sashes *e* and *f* of different widths, one being wider than the other but the combined width of the two being equal to the width of the frame in order that when closed the two sashes will meet.

Stops *x*, *x* are provided to limit the movement of sashes *e* and *f*.

To the back of the frame are hinged two further sashes *g* and *h* of substantially the same width, both being wider than half the width of the frame in order that when closed they will overlap. A stop *i* is provided to prevent the sash *g* opening outwards and a further stop *j* is provided to limit the movement of the sash *h*.

In use the sashes may be set as shown in Fig. 1 or the sash *h* may be opened inwards a little further and the air will have to zig-

zag through a tortuous path in order to enter the room, all external sounds being thereby muffled.

Provision may be made for catching rain water by making the base *d* of the window in the form of a hollow box with holes at top for allowing the water to drop into the hollow container or receptacle which has a waste pipe for carrying the water off.

What I claim and desire to secure by Letters Patent is:—

1. A casement window comprising a rectangular frame and four sashes, hinged at their sides to the front and the back of the two sides of the frame respectively, one pair of sashes when closed being adapted to close the front of the frame and not to overlap and the other pair being of a size adapted to close the back of the frame and to overlap to a substantial degree.

2. A casement window comprising a rectangular frame and four sashes, hinged at their sides to the front and the back of the two sides of the frame respectively, one pair of sashes when closed together being adapted to close the front of the frame and not to overlap and the other pair being of a size adapted to close the back of the frame and to overlap to a substantial degree together with one or more stops adapted to prevent the two overlapping sashes from meeting together and to prevent the non-overlapping sashes from opening in an outward direction.

In testimony whereof, I affix my signature.

CHARLES SAMUEL CLARKE.
